CLAIM

The ornamental design for a network cable setup and installation tool, as shown and described.

DESCRIPTION

FIG. 1 is a top front right perspective view of a network cable setup and installation tool showing our new design.

FIG. 2 is a bottom rear left perspective view thereof.

FIG. 3 is a front elevational view thereof.

FIG. 4 is a rear elevational view thereof.

FIG. 5 is a right side elevational view thereof.

FIG. 6 is a left side elevational view thereof.

FIG. 7 is a top plan view thereof.

FIG. 8 is a bottom plan view thereof.

FIG. 9 is a top front right perspective view of another embodiment of a network cable setup and installation tool showing our new design.

FIG. 10 is a bottom rear left perspective view thereof.

FIG. 11 is a front elevational view thereof.

FIG. 12 is a rear elevational view thereof.

FIG. 13 is a right side elevational view thereof.

FIG. 14 is a left side elevational view thereof.

FIG. 15 is a top plan view thereof; and,

FIG. 16 is a bottom plan view thereof.

The broken lines shown in the drawings are for the purpose of illustrating portions of the network cable setup and installation tool that form no part of the claimed design.
